UNITED STATES PATENT OFFICE.

KNUT HELMER OBERG, OF NELSON, BRITISH COLUMBIA, CANADA.

COMBINATION LOCK.

Application filed October 18, 1923, Serial No. 669,271. Renewed July 18, 1925.

This invention relates to improvements in combination locks and its object is to provide a simple practical device of this type capable of a variety of uses. With the foregoing and other objects in view the invention consists in the combination and arrangement of parts to be hereinafter fully described, pointed out in the appended claims and illustrated in the accompanying drawing which forms a part of this application and in which—

Fig. 1 is a face view of the lock.

Fig. 2 is a fragmentary view, the dials being removed.

Fig. 3 is a fragmentary rear view disclosing the mechanism for actuating the bolt.

Fig. 4 is a fragmentary view of the bolt-receiving casing.

Like reference characters denote corresponding parts throughout the several views.

The reference numerals 1, 2 denote the annular frame members between which is secured the annular rack 3 to which the ends of the span bar 4 are secured which supports the spindle 5 whereon the rotary circular rack 6 is arranged, said rack being formed with a recess 7 and being in the plane of the rack 3 but spaced away therefrom to receive the pinion 8 that is in mesh with both racks 3 and 6, said pinion being arranged upon the shaft 9 that is disposed between the members 3 and 6 and that extends outwardly through a slot 10 in the frame member 1 and is provided with the knob 11 whereby it is rotated to cause rotation of the said pinion. By rotation of the knob 11 the shaft 9 is rotated together with its pinion 8 which rotates the rack 6.

A link 12 is formed with a perforation in one end to snugly receive the shaft 9 which passes therethrough, rotation of the shaft 9 serving yieldingly to swing the link 12 about it as a pivot. The opposite end of the said link, however, is pivotally secured to the bolt 13 formed with an elongated slot 14 through which the spindle 5 passes, said bolt 13 and link 12 being disposed upon the same side of the rack 6 as the span bar 4. The bolt 13 is pivotally and slidably supported upon the said spindle 5 and said bolt is provided with a lug 15 which in the extended position of the bolt 13, shown in Fig. 3, is disposed between the racks 3 and 6. When the shaft 9 is rotated the rack 6 is rotated, the lug 15 riding over the teeth of said rack until the recess 7 aligning with

the said lug receives the same and permits the link 12 to retract the bolt 13. In locked position the bolt 13 extends beyond the periphery of the frame members 1, 2 into the bolt casing 16.

Three links 17, 18 and 19 pivotally carried by the frame member 1 are adapted for releasable engagement, by means of thumb-screws (not shown) extending through the perforations 20 in their ends, for engagement respectively with the rotary dials 21, 22, 23 to retain them in adjusted position relatively. When one dial is positioned, as dial 21, the link 17 is then engaged with it temporarily so that it will not be moved by friction of the spindle 5 while dial 22 is being set. Dial 22 is held in adjusted position by link 18 while dial 23 is being set. Each of said dials is centered upon the spindle 5 loosely and is formed with graduations 24. Each dial 22, 23 is provided with an indicator 25 and the frame member 1 with a similar indicator 25, the indicator 25 of dial 22 working in connection with the graduations 24 of dial 21; the indicator of dial 23 referring to the graduations of dial 22 and the indicator of frame member 1 pointing to the graduations of the dial 23. Each dial, further, is provided with a knob 26 whereby it is rotated. The three dials are, however, but blinds or idlers to camouflage the real mechanism. The operator may position the dials relatively to suit his fancy by means of the knobs 26 but when he wishes to unlock the device he rotates the knob 11 and so turns the disc 6 until its recess 7 will receive the lug 15. In the extreme inner or retracted position of the bolt 13, with the lug 15 at the inner termination of the recess 7, the device is unlocked and the bolt 13 withdrawn from the casing 16. Rotation of the knob in the opposite direction will force the bolt outwardly thus locking the device.

What is claimed is—

1. In a lock, a casing, a rack carried thereby, a span bar carried by said rack, a spindle carried by said span bar, a rotary rack centered upon said spindle within the first rack and formed with a peripheral recess, a bolt pivotally and slidably carried by said spindle, a lug carried by said bolt for disposal between said racks and capable of disposal in the said recess, means connecting said racks and said bolt whereby the latter is actuated, and a casing for said bolt.

2. In a lock, a casing, a rack carried thereby, a span bar carried by said rack, a spindle carried by said span bar, a rotary rack centered upon said spindle within the first 5 named rack and formed with a peripheral recess, a bolt pivotally and slidably carried by said spindle, a pinion connecting the aforesaid racks, a shaft carrying said pinion, connection between said shaft and bolt, a lug 10 carried by said bolt for disposal in the said recess in said rotary rack, and a casing for said bolt.

3. In a lock, a casing, a stationary rack carried thereby, a span bar carried by said 15 stationary rack, a spindle carried by said span bar, a rotary recessed rack arranged upon said spindle and spaced away from the stationary rack, a bolt arranged upon said spindle, a lug carried by said bolt capable 20 of disposition in the recess of said stationary

rack, means connecting said racks and bolt whereby said rotary rack and bolt may be actuated and caused to cooperate with each other, and a casing for said bolt.

4. In a lock, a casing, a stationary rack 25 carried thereby, a span bar carried by said stationary rack, a spindle carried by said span bar, a rotary recessed rack arranged upon said spindle and spaced away from the stationary rack, a bolt arranged upon 30 said spindle, a lug carried by said bolt for movement into and out of the recess in said rotary rack, means connecting said racks and bolt whereby said rotary rack and bolt may be actuated, graduated dials arranged upon 35 said spindle for cooperation with each other, and a casing for said bolt.

In testimony that I claim the foregoing as my own I have hereto affixed my signature.

KNUT HELMER OBERG.
